DESIGN FOR A HYDRANT

Application filed January 29, 1932. Serial No. 42,676. Term of patent 14 years.

To all whom it may concern:

Be it known that we, WILLIAM H. LOLLEY, a citizen of the United States, and residing in the city of Albany, county of Albany, and State of New York, BJORNULF JOHNSEN, a citizen of the United States, and residing in the city of Brooklyn, county of Kings, and State of New York, and FRED L. WHEELER, a citizen of the United States, and residing in the city of Troy, county of Rensselaer, and State of New York, have invented a new, original, and ornamental Design for a Hydrant, of which the following is a specification, reference being had to the accompanying drawings, forming a part thereof.

Figure 1 is a view, in elevation, of a hydrant showing our new design.

Figure 2 is a plan view, looking from above in Figure 1.

The dominant feature of the design is the configuration. It is contemplated that the hydrant may be made in contrasting colors, as indicated by the shaded and unshaded portions.

We claim:

The ornamental design for a hydrant as shown, and described.
